UNITED STATES PATENT OFFICE.

EDWIN BIRD WILSON, OF FOREST HILLS, NEW YORK, ASSIGNOR TO DESIGN LABORATORIES, INCORPORATED, OF NEW YORK, N. Y., A CORPORATION OF NEW YORK.

FIGURE TOY.

Application filed December 7, 1923. Serial No. 605,486.

This invention relates to toys of an improved and novel structure, particularly to the class of toys such as dolls and toy animals constituting effigies, usually but not 5 always of living beings, and to an improved and novel method of making such toy effigies adapted to assume a plurality of different expressions and postures.

One of the objects of this invention is to 10 provide a novel type of effigies which may be caused to assume and retain a great variety of shapes, attitudes, and particularly of expressions, whether of the head and face or of the body or other members.

Another object is to provide a structure 15 for such effigies which, in the hands, for example, of an infant, will have practically the softness and durability of a rag doll or the like, with the attendant lack of danger 20 to the infant, and which will combine with this the ability to execute a variety of facial and other changes such as the ability to open and close the eyes and mouth, to smile, to frown, to assume a laughing expression, to change from fat to lean, to 25 move the nose or ears, to elongate the limbs, etc., in short, the ability to assume and to retain a very great variety of postures and expressions both as a whole and as affecting 30 individual features.

A further object is to provide an effigy 35 which is alterable from any one to any other of a great range of postures and facial expression by a simple pressure or blow, and in which the postures and expressions are studied by the designing artist, predetermined, will be retained as long as desired, and can each again be reproduced at will.

Another object of my invention is to 40 provide a new medium for ingenious artistic representations, particularly of human faces though not limited to those, with representation of play of emotion and sequence of facial expression. Effigies made according to 45 this invention may be surprisingly life-like, and a new range of interesting, artistic and amusing effects is opened up by the control of series of facial and bodily expressions and contortions. This invention adds as it 50 were another dimension to the work of the toy designing artist, in that if he be designing a doll's head, for example, he has to consider the effects of his drawing through a series of changes of shape plus a series of 55 relative displacements and distortions of

separate features. In constructing, for example, a doll in accordance with my invention, a considerable part of the artist's ingenuity must be expended on the proper choice to suit his subject of the multitude of displacements that may be given to any or all features. 60

Preferably, the above outlined objects are attained by providing an elastic fabric or the like bearing the drawing, painting or other representation of the face, animal's head, body or object intended. The material used for this may be thin rubber, so called chamois skin, soft kid, a knitted fabric of wool, of silk, of cotton, etc., or any 70 material of strength and elasticity sufficient for the purpose. This elastic medium is mounted on a distortable frame. This frame may be constructed in many ways and of a great variety of materials. A 75 few preferred embodiments thereof are hereinafter disclosed, which, in accordance with a feature of the present invention, comprise substantially a loop or outer frame member of stiff but somewhat pliable material—such as a thin spring or flat wire, or a whalebone, a wooden hoop, etc. This loop being somewhat pliable may be distorted by pressure and in accordance with still a 80 further feature of this invention, is held 85 in its distorted shape by frictional or other suitable means.

The above mentioned elastic cover over the frame will stretch and shorten along different axes responsive to the distortion of 90 the frame and the drawing, modeling or painting thereon will be distorted in accordance.

By any given change of shape of the frame an increased tension with stretching 95 occurs in some direction through all points of the elastic cover, and a decreased tension with shortening occurs in a direction substantially normal to the first. Either the stretching or the shortening of selected portions of the elastic cover may be prevented or opposed for any given range of distortions by proper connecting links, such as stiffeners, tapes, rubber bands, strings, etc., attached to said portions and to other points 100 of said cover, notably points adjacent the frame, or even to the frame. By this means, features or details movable in life may be caused to move or change shape with life-like or grotesque effects. 105 110

I have devised also a novel method of assembling an effigy, for instance a doll's head, embodying the use of connecting links as just described. It consists in attaching 5 the connecting links at one of their ends to selected points preferably on the under side of the elastic cover bearing the representation, of then applying this cover to a distortable frame and attaching it leaving the 10 loose ends of the connecting links unattached. The frame is then distorted to a predetermined extent, the links are drawn or pushed until the desired local distortion or shade of expression is obtained, and the links are 15 then made fast either to the frame or to any portion, for instance an inner lining, of the effigy.

Many other interesting effects can be obtained by another use of an inner lining, 20 which may be attached either to the frame or to the outer elastic cover. For instance, certain features, sometimes in life not visible, as teeth, tongue, eyeballs, etc., may be depicted on such an inner lining, and slits or 25 openings may be provided in the outer elastic cover to open by the distortion thereof, with or without the use of connecting links, and to disclose such hidden features.

It will be clear that I could not attempt 30 to disclose any considerable fraction of the artistic or amusing exemplifications or applications of my invention, since these applications lie mainly in the field of the imaginative designer and artist. The many particular artistic or amusing forms my invention may take must be left to those skilled in the arts of representation, before whom I believe a novel field is hereby opened. In any case 35 my invention is not limited to application to the particular form shown in the drawings, being a female doll's head, but many other and as yet unimagined outer forms or applications may, within the spirit of this invention, be made of the disclosed structure or of 40 its equivalent.

The features above outlined and others 45 will more clearly appear from the following detailed description of structures exemplifying certain preferred embodiments of the present invention. The structure herein disclosed may be widely varied without departing from the spirit of the present invention the scope of which is defined in the appended 50 claims.

In the drawings four embodiments of the 55 frame structure, together with the application of one of them to a doll's head, are disclosed.

Fig. 1 is a plan view of the preferred 60 embodiment. Fig. 2 is a sectional view along the line 2—2 of the friction clamp of Fig. 1. Fig. 3 is a plan view of an alternative frame structure. Fig. 4 is an elevation of one of the two punchings 21 forming the stops in frame Fig. 3. Fig. 5 is a plan 65

view of a third modified frame. Fig. 6 is a plan of a fourth modification of this frame. Fig. 7 is a cross section of a doll's head along the line 7—7 of Fig. 10. Fig. 8 is a front view of a doll's head, constructed 70 on any of the frames Figs. 1, 3, 5 or 6 but preferably on frame Fig. 1, showing the head when the frame is in its natural circular or not distorted condition. Fig. 9 is a front view of the same doll's head when 75 the frame is vertically elongated. Fig. 10 is a front view of the same doll's head with the frame horizontally elongated. Fig. 11 is a side elevation of a portion of the face and of the nose of the head of Fig. 8. Fig. 12 is a vertical sectional view through the center of the nose and mouth of Fig. 9.

In Fig. 1, 1 is a loop shaped frame formed of a thin wide ribbon of resilient material such as spring steel. 2 is a channel shaped 85 punching of which there are two, enclosing the ends of loop 1 to hold them together at the neck of the frame. 3 is a wrapping of wire or of cord holding the channel punchings 2 in place, 4 is a rectangular friction rod 90 frictionally engaged between the two ends of loop 1 which at this point are formed so as strongly to press against it. 5 is a thin metal U-shaped strap enclosing loop 1 at the top and having both ends fastened by pivot 95 screws 6, of which there are two, to the upper end of friction bar 4. Owing to the flexibility of the loop 1, U-shaped strap 5 has a limited swinging movement about pivot screws 6. 7 is a spacer block lying between 100 the two parts of 5 and fastened thereto by screws 8 from both sides. A screw 9 through a hole in the top portion of strap 5 and through a hole in the top of loop 1 clamps loop 1 to spacer block 7 and to strap 105 5. 10 is a horizontal stop bar held in place in strap 5 by screws 11 of which there may be four. The corners 12 of strap 5 serve to limit the distortion of the frame in the one direction by striking on the loop 1 at points 110 13. The loose ends of loop 1 are formed outward at 14, as may be most suitable for attachment to the body or remaining portion of the effigy. Friction bar 4, spacer block 7 and horizontal stop bar 10 are economically 115 made of wood but may be of any suitable light material such as fibre or the like. Pivot screws 6 and screws 8 and 11 may be replaced by rivets or nails.

In Fig. 3, 15 is a loop formed of a relatively wide ribbon of thin resilient material such as spring steel. 16 is an attachment portion for the same purpose as formed ends 14 in Fig. 1. 17 and 18 are respectively, split friction bushings and friction plungers. Each plunger 18 cooperates with bushing 17 to form a frictional telescopic cross member. One of these friction cross members comprising bushing 17 and plunger 18 extends across the loop 15 horizontally 130

and the other member extends across the loop 15 vertically. The two members are in different planes so as not to interfere. The bushing and plunger 17 and 18 are 5 shouldered at their outer ends to form a rivet portion. These rivet portions pass through holes in loop 15 and are riveted over at 20 and 19 for firm attachment to loop 15. The rivet portion 19 further 10 passes through both ends of loop 15 and through a hole in the center of attachment member 16 serving to hold the loop closed and to attach member 16. Freely enclosing the crossing of the two telescopic friction 15 members are two punched stop plates 21 in each of which is formed a channel portion 22, best seen in Fig. 4, of sufficient depth to accommodate a bushing 17. These two punchings 21 are assembled by screws 23 20 through holes 24 with their channels 22 at right angles to each other so that the two assembled stop plates ride loosely on the two transverse friction members and maintain substantially a central position within 25 the loop 15. The ends of the bushings 17 striking against loop 15 serve to limit the distortion of this frame in either direction. The ends of the arms of the stop plates 21 serve to prevent the collapsing of spring 30 loop 15 if undue pressure is applied at a point between any two rivets 20, or 20 and 19.

In Fig. 5, 25 is a loop formed of a thin 35 relatively wide ribbon of resilient material such as spring steel. It is formed to a neck at 26 and the ends 27 are formed for convenient attachment to another portion of the effigy. 28 is a loop of relatively stiff but non-resilient or malleable material such 40 as lead or soft aluminum or even soft copper. 29 is an inner loop of the same material as 25. 30 is a wire wrapping holding 25, 28 and 29 in close contact. The stiffness or inability to make short bends of spring 45 loops 25 and 29 insure that the deformations of this frame shall be smooth and sweeping. The lack of resilience of malleable loop 28 insure that deformations imparted to this frame will be retained. 31 50 is a vertical stop bar held by rivets 32 at the neck 26 of outer loop 25. 33 is a horizontal stop rod driven through vertical stop bar 31.

In Fig. 6, 34 is a loop of relatively thin 55 wide resilient material such as spring steel, formed at 35 to a neck and with the ends 36 formed for convenient attachment to other parts of the effigy. 37 is a channel shaped member similar to member 2 of Fig. 62 and for the same purpose, namely to hold together the neck portions of loop 34. There are two channel shaped members 37. 38 is a wrapping of wire or cord to hold the assemblage together. 39 is a friction member 65 constructed of a strip of metal of sub-

stantially the same width as the metal of loop 34 but somewhat thicker and stiffer. It is bent back upon itself forming at 40 an enlargement which when drawn up to strike the corners 41 of the outer loop 34, 70 limits the vertical elongation of this frame. 42 is a rivet inserted through the two portions of friction member 39 and has the double purpose of holding them together, and of limiting the horizontal elongation 75 of the frame by striking the corners 43 of loop 34. The ends of friction member 39 are bent outwardly at 44 and attached to the upper section of loop 34 by wire wrapping 45. 80

In Fig. 7, which is a cross section on line 7-7 of Fig. 10, 1 is the loop shaped frame of Fig. 1, 4 is the rectangular friction bar, 5 the U-shaped strap and 6 the pivot screw all as shown in Fig. 1. 46 is the resilient 85 casing of the back of the doll's head, 47 the resilient inner casing of the front of the doll's head, 48 a strip of fabric sewed to loop 1, and to which 46 and 47 in turn, are sewed. 49 is the outer resilient casing bearing the 90 representation of the face of the effigy, 50 is a link connecting two points of the outer casing on either side of the chin. 51 are wrinkles in this casing formed when the frame is horizontally elongated, as shown 95 in Fig. 10, and simulating dimples. 52 are links from the lower portion of fabric strip 48 to the lower eyelids as seen best in Fig. 10, and 53 is the resilient filling of the head such as curled hair, wool, feathers or any 100 elastic material. If the elastic casings 46 and 47 are made of thin sheet rubber or suitably rendered impervious as suggested above, the filling 53 may consist of air under a slight pressure. 105

In Fig. 8, 54 is a membrane or portion of fabric formed to represent a nose and painted or marked in accordance. It is cemented or sewed around its edges to the outer front casing 49 and filled with an elastic material 110 such as wool, hair etc. 55 are the portions of the outer casing forming the upper eyelids of the effigy and attached by tapes 56 to the strip of fabric 48 on frame 1 at a point near the top of the head. The lower edge of these upper eyelids 55 is sewed or cemented to the inner casing 47. 57 are eyebrows depicted on the outer casing, 58 are narrow elastic tapes or rubber bands attached to the outer casing near the inner ends of said eyebrows and attached to the strip of fabric 48 at the upper part of the head. 59 are slits in the outer casing suitably camouflaged by embroidered or painted eyelashes 60. 61 are 115 eyeballs depicted on inner casing 47 and in 120 Fig. 8 shown dotted. 62 is a stiff link of thin fibre or celluloid or the like attaching at a fixed distance from each other the inner ends of the eyes. 63 are similar links attaching the outer ends of the eyes to strip of 130

fabric 48 on either side of the head, whereby the size of the eyes are caused to vary as the frame 1 is distorted. 64 is the representation of a mouth on the outer casing, 65 a slit in said casing at the proper point to enable the mouth to be opened. 66 is a representation of tongue and teeth upon the inner casing 47, best seen in Fig. 9, adapted to be exposed when the slit 65 is drawn open. 67 10 are tapes from the corners of the mouth to the sides of the frame, 68 is a tape from the lower lip of mouth 64 to the lower portion of the frame, 69 is a similar tape from the upper lip to the upper portion of the frame. 15 70 is a cord attached to the inside of the tip of the nose 54 and passing through the outer casing 49 and attached to the top portion of the frame. All of these links 50, 52, 56, 58, 62, 63, 67, 68, 69 and 70 are preferably arranged to lie between the inner casing 47 and the outer casing 49.

In Fig. 10 the action of links 62 and 63 in extending the eyes when the frame is horizontally elongated is shown. In Fig. 9 25 action of these same rigid links in somewhat narrowing the eyes when the frame is vertically elongated is shown.

In Fig. 9 action of tapes 67 in widening the mouth is shown as also the action of tape 30 50 in producing dimples 51 as mentioned above. Further, in Fig. 9, the effect of elastic bands 58 in raising the eyebrows is illustrated; also the action of tapes 52 and 56 in causing the eyes to open when the head is 35 vertically elongated. Tapes 69 and 68 are also shown in this view pulling open slit 65 of mouth 64 and disclosing, as mentioned above, teeth and tongue 66 depicted on the inner casing. Further, in this view, cord 70 40 is shown drawing upward the tip of nose 54. In Fig. 12, which is a vertical cross section through the nose and mouth of Fig. 9, the connection of cord 70 to the inside of the tip of nose 54 is more clearly shown. The filling 45 71 of nose 54 is also shown. The action of tapes 68 and 69 in pulling open slit 65 of mouth 64 to disclose a portion of the surface of inner casing 47 is also more clearly illustrated in Fig. 12.

50 Obviously, the links, by which the various features of the face may be distorted, may be varied and combined at will without departing from the spirit of the invention. Rigid or elastic links may be used throughout the 55 structure, or substituted one for the other according to the effect desired.

What I claim is:

1. The method of making effigies adapted to assume a plurality of different expressions 60 consisting in: attaching one end of a link to a casing bearing a representation of an effigy at a certain point of the representation, attaching the casing to a distortable frame while leaving the other end of the link free and accessible, giving to the frame a desired 65

distorted shape, moving the link until the change in the representation is obtained that it is desired to produce by the particular shape given the frame, and finally attaching the free end of the link to the frame maintaining it while so doing in the position to which it has been moved. 70

2. The method of making effigies adapted to assume a plurality of different expressions 75 consisting in: reproducing on an elastic casing a representation of the effigy, attaching one end of a link to the casing at a certain point of the representation of the effigy, stretching the casing on a distortable frame while leaving the free end of the link accessible, distorting the frame to a certain shape, stressing the link until the change in the representation is obtained that is intended to accompany that particular shape of the frame, and finally making fast the free end 80 of the stressed link to or near the frame. 85

3. As a new article of manufacture, an elastic casing, a distortable frame, a filling of yielding material within said elastic casing which casing bears a representation of an effigy, said casing being stretched on and stressed by said distortable frame, and non-elastic connections between certain portions of the casing and the frame for further stressing said casing at certain points responsive to distortion of the frame. 95

4. In an effigy, a semi-rigid substantially loop shaped distortable frame, means for retaining said frame in certain shapes it may assume, a yielding filling, an elastic 100 casing stretched over said frame and enclosing said filling, and representation of a portion of the effigy on said elastic casing.

5. In an effigy, a substantially loop-shaped frame of thin resilient material capable of 105 distortion in the plane of the loop, a friction device connected with said frame for retaining it in certain distorted forms it may assume, a yielding filling, an elastic covering stretched over said frame and enclosing said filling, and representations of portions of the effigy on said elastic covering. 110

6. In an effigy, the combination of an elastic casing bearing representation of the effigy, yielding filling for said casing, a frame of relatively rigid material on which said elastic casing is stretched and which is arranged to be forced into a plurality of shapes, and means for holding said frame in the shape into which it has been forced. 115

7. In an effigy, a distortable frame, an elastic covering stretched over said frame, a representation upon said covering of a portion of the effigy and distorted by distortion of said frame, and elastic connections between certain portions of said covering and said frame for opposing the distortion of certain portions of said representation. 125

8. In an effigy, a distortable frame, an elastic covering stretched over said frame, a 130

representation upon said covering of a portion of the effigy and distorted by distortion of said frame, and draw-strings attached to certain portions of said covering and frame

5 for opposing the distortion of certain portions of said representation.

9. In an effigy, a distortable frame, an elastic covering stretched over said frame, a representation upon said covering of a portion of the effigy and distorted by distortion of said frame, and non-elastic members interconnecting certain portions of said covering with said frame for opposing the distortion of certain portions of said representation.

10. In an effigy, a distortable frame, an elastic covering stretched over said frame, a representation upon said covering of a portion of the effigy and distorted by distortion of said frame, and means for opposing the distortion of certain portions of said representation.

11. In an effigy, a distortable frame, an elastic casing bearing a representation of the effigy stretched over said frame, and a non-elastic connection between a certain point of the casing and a certain point of the frame for distorting certain portions of said effigy in a predetermined manner upon distortion of said frame.

12. In an effigy, a distortable frame, means for holding said frame in any one of a plurality of distorted shapes, an elastic casing having depicted upon it a portion of the effigy and being stretched over said frame, and a plurality of connections each with one end attached to said casing at some point of the depicted effigy and with the other end attached to a part of said frame.

13. In an effigy, a substantially loop-shaped distortable frame, an elastic casing bearing a representation of the effigy stretched over said frame and distortable therewith, and means interconnecting a particular point of said elastic casing and said frame for applying a stress to said point of said casing responsive to distortion of said frame.

14. In an effigy, a substantially loop-shaped distortable frame, an elastic casing bearing a representation of the effigy stretched over said frame and distortable therewith, a link interconnecting a point of said casing and a point of said frame for applying stress to said point of said casing, substantially in the plane of the casing, responsive to a predetermined distortion of said frame.

15. As a new article of manufacture, a substantially loop-shaped distortable frame, an elastic covering attached thereto and a portion of an effigy represented thereon, a linkage for connecting two points of said covering and maintaining between them, upon certain distortions of said frame, a

distance differing from the distance which would intervene between the two said points if the said linkage were not interconnected between the points.

16. In an effigy, a substantially loop shaped frame capable of limited distortion, distortion retaining means, a yielding filling material, a first elastic covering stretched over said frame and enclosing said filling material, an outer elastic covering bearing representations of portions of the effigy stretched over said frame, connections lying between said first and said outer coverings connecting portions of said outer covering to portions of said frame.

17. In an effigy, a substantially loop shaped spring frame distortable in the plane of the loop, a friction member across a portion of said loop to retain said frame in any one of a plurality of forms, stop members limiting the distortion of said loop, a yielding filling material, a first elastic covering stretched over said frame and enclosing said filling material, an outer elastic covering surrounding said first elastic covering and bearing a representation of a face comprising features, and an attachment between a point of said outer covering and an appropriate point of said first covering.

18. In an effigy, a substantially loop shaped spring frame capable of distortion in the plane of the loop including distortion retaining means, a yielding filling, a knit outer covering stretched over said frame bearing representation of a portion of the effigy, said covering enclosing said yielding filling, connections within said outer covering connecting portions thereof to portions of said frame whereby details of the representation on said outer covering are individually distorted when said frame, outer covering and filling are given certain distortions as whole.

19. In an effigy of a head, a distortable substantially loop shaped frame, a yielding filling, an inner elastic covering over said frame and a portion of said filling, an outer elastic covering surrounding said frame bearing a representation of features including eyes normally closed, a lower eyelid forming a portion of the outer covering, an upper eyelid also forming a portion of the outer covering severed from said lower eyelid and attached to said inner elastic covering, a drawstring connecting said upper eyelid to the frame at the upper portion of the head, an eyeball depicted upon said inner covering immediately below the point of attachment of said upper eyelids to said inner covering.

20. In an effigy of a head, a distortable substantially loop shaped frame, a yielding filling, an inner elastic covering over said frame and a portion of said yielding filling, an outer elastic covering surrounding said

- frame and bearing a representation of features including eyes normally closed, a lower eyelid forming a portion of the outer covering, an upper eyelid also forming a portion 5 of the outer covering severed from said lower eyelid, an eyeball depicted upon said inner covering, and means responsive to the distortion of said frame for displaying said eyeball.
- 10 21. In an effigy of a head, a substantially loop shaped distortable frame, a yielding filling, an inner elastic covering over said frame and a portion of said filling, an outer elastic covering over said inner covering 15 surrounding said frame and bearing a representation of a mouth, lips forming portions of said outer covering, a representation of the interior of a mouth depicted on the

inner elastic covering, and means responsive to the distortion of said frame for displaying 20 the interior of the mouth.

22. In an effigy, a substantially loop shaped distortable frame, a yielding filling, an inner covering, an outer elastic covering bearing a representation of a portion of an effigy and attached to said frame, an opening in said outer elastic covering, and means operated when said frame is distorted to a certain extent for moving said opening to uncover a portion of said inner covering and a representation depicted upon the uncovered portion of said inner covering. 25

In witness whereof, I hereunto subscribe my name this sixth day of December, 1922.

EDWIN BIRD WILSON.
